UNITED STATES PATENT OFFICE

137,654

DESIGN FOR A SMOKING STAND

Jacob Goldberg, Springfield, Pa., assignor to
G & R Mfg. Co., Philadelphia, Pa., a partnership

Application September 16, 1943, Serial No. 111,135

Term of patent 3½ years

(Cl. D85—2)

To all whom it may concern:

Be it known that I, Jacob Goldberg, a citizen of the United States, residing in Springfield, in the county of Delaware, State of Pennsylvania, have invented a new, original, and ornamental Design for a Smoking Stand, of which the following is a specification, reference being had to the accompanying drawing, forming part thereof.

Fig. 1 is an elevational view of a smoking stand showing my new design.

Fig. 2 is a central vertical section.

Fig. 3 is a horizontal section on line 3—3 of Fig. 1.

Fig. 4 is a top plan view.

Fig. 5 is a view in perspective of the bowl.

Fig. 6 is an enlarged detail view of the ornamentation around the base of the stand.

I claim:

The ornamental design for a smoking stand, as shown.

JACOB GOLDBERG.
